UNITED STATES PATENT OFFICE.

PAUL A. MEEHAN, OF NEW CASTLE, PENNSYLVANIA, ASSIGNOR TO AMERICAN DRESSLER TUNNEL KILNS, INC., OF NEW YORK, N. Y., A CORPORATION OF NEW YORK.

TUNNEL-KILN.

1,348,511.

Specification of Letters Patent.

Patented Aug. 3, 1920.

Application filed December 5, 1919. Serial No. 342,724.

To all whom it may concern:

Be it known that I, PAUL A. MEEHAN, a citizen of the United States, and a resident of New Castle, in the county of Lawrence 5 and State of Pennsylvania, have invented certain new and useful Improvements in Tunnel-Kilns, of which the following is a specification.

My present invention relates to kilns and 10 particularly to kilns of the tunnel type in which the kiln chamber is heated by combustion chambers disposed longitudinally of the kiln chamber.

The general object of the present invention is to provide a special kiln heating combustion chamber construction and arrangement whereby the overall length of a combustion chamber necessary for effective combustion and the effective utilization of the 15 heat of combustion may be substantially reduced. To accomplish this object I form my combustion chambers internally with two passages which communicate with one another at one end of the combustion chamber and at the opposite end are connected one with air and fuel inlets and the other to an outlet for products of combustion. I thus provide a path for the burning gases which is practically twice as long as the 20 combustion chamber structure. My present invention is of especial utility in a kiln such as that used for baking enamel on goods in which the heating up and cooling zones ordinarily provided in a tunnel kiln are unnecessary, and it is desirable to heat a comparatively short kiln chamber uniformly from 25 one end to the other. My improved combustion chambers are not restricted to use in any particular type of kiln, however, but 30 are adapted for use wherever a relatively short combustion chamber is desirable.

The various features of novelty which characterize my invention are pointed out with particularity in the claims annexed to 35 and forming a part of this specification. For a better understanding of the invention, however, and the advantages possessed by it, reference may be had to the accompanying drawings and descriptive matter in which I 40 have illustrated and described a preferred embodiment of my invention.

Of the drawings:

Figure 1 is a plan view in section of the body portion of a kiln.

Fig. 2 is an elevation partly in section on 55 the broken line 2—2 of Fig. 1.

Fig. 3 is a section on the line 3—3 of Fig. 2.

Fig. 4 is an illustration showing a modified form of combustion chamber construction, and 60

Fig. 5 is a view taken similarly to Fig. 4 illustrating a second modified form of kiln combustion chamber construction.

In the drawings I have illustrated the use 65 of my invention in a kiln comprising a kiln chamber A proper inclosed by a refractory wall B, and having benches B' which are located at opposite sides of a pathway for goods carrying cars F, and each support a 70 combustion chamber G, the two chambers G being of similar construction. The cars have wheels running on track rails E. In the respects just noted the construction is that of the ordinary Dressler type of kiln as 75 shown for example in patents granted to Conrad Dressler #1,023,628 and #1,170,428.

In the kiln specifically illustrated herein, the goods carrying cars are introduced into one end of the kiln chamber proper past a 80 doorway normally closed by a door D, from an antechamber C and pass out of the opposite end of the kiln chamber proper through a doorway normally closed by a door D' into an exit chamber similar to the ante-chamber C.

Each combustion chamber G is internally divided into two chambers or passages by a longitudinal partition so that the products of combustion pass through the combustion 90 chamber from one end to the other along one side of the partition and then return to the other side of the partition to an exit port located at the same end of the combustion chamber at which air and fuel inlet 95 ports are located. In the construction shown in Figs. 1, 2 and 3 the longitudinal partition I is formed of a flat plate or plates of refractory material mounted on supports I¹. The outer walls of each combustion 100 chamber G are formed, as is usual in Dressler kilns, of sections H of hollow refractory tile having open ended passages H¹ through which the kiln atmosphere flows upwardly across the combustion chambers and is 105 heated in its passage, and then passes downward over the goods, heating the latter and being thereby cooled, thus maintaining a

gravity circulation of the kiln atmosphere. At one end of each combustion chamber G, a masonry end portion J is provided which is formed with an air inlet passage J¹ communicating at its lower end with an air supply conduit J³, and having a horizontal upper portion opening directly to the chamber portion g of the combustion chamber above the partition I. A fuel supply nozzle 5 K leads through the end wall of the kiln into the upper horizontal portion of the air passage J¹. The end member J is also provided with an outlet passage J² leading from the chamber g¹ below the partition I to the 10 exit conduit J⁴. The opposite end of the combustion chamber is closed by an end member L of refractory material and the partition I stops short of this end member, as shown in Fig. 2, to thereby establish communication between chamber portions g and g¹. Regenerators, recuperators or other suitable apparatus may be employed, when desirable, to preheat the air supplied to the combustion chambers through the tunnels 15 J³ and for utilizing the sensible heat in the products of combustion issuing from the combustion chambers through the passage J² and conduit J⁴, but I have not illustrated such apparatus as suitable forms of such 20 apparatus are well known and their particular form or construction constitutes no feature of the present invention.

The kiln shown is especially devised for use in baking enamel on bath tubs and for 25 like purposes. The combustion chambers A extend practically the full length of the kiln chamber proper. Combustion is initiated in one of the combustion chambers at one end of the kiln, and at the opposite end of the 30 kiln in the other combustion chamber so that variations in temperatures lengthwise of one combustion chamber are substantially compensated for under normal operation by variations in the other combustion chamber. 35 In the respect just noted the kiln illustrated is like that disclosed and claimed in my co-pending application, Serial #342,723 filed of even date herewith.

In the modified form of combustion chamber illustrated in Fig. 4 the partition IA separating the chambers g and g¹ of the combustion chamber is formed of tile sections similar to those forming the outer walls of the combustion chamber. The ventilating or circulating passages I¹⁰ in the tile forming the partition IA communicate at their ends with the corresponding circulating passages H¹ of the vertically disposed walls of the combustion chamber. To insure a gravity circulation through the circulating passages in the partition IA, the latter is slightly inclined to the horizontal as shown.

In the modification illustrated in Fig. 5, 60 the partition IB, dividing the two portions

g⁵ and g⁶ of the combustion chamber, is vertically disposed and is in the form of a platelike body of refractory material having upper and lower edge portions I⁵ and I⁶ bearing against the adjacent surfaces of the 70 upper and lower walls of the combustion chamber.

In each of the different forms of combustion chamber illustrated, heat is effectively abstracted from each leg of the loop shaped 75 flame path, and the heating effect of the combustion chamber as a whole at any point along its length is a joint function of the temperatures of the two legs of the loop at that point.

It will be apparent to those skilled in the art that the special combustion chamber construction illustrated is simple and effective and that it practically halves the overall length of the kiln section occupied by a combustion chamber having the length of flame path required for the effective combustion of a given amount and kind of gas. At the same time, the amount of heat available for abstraction by the goods per unit length of 80 kiln is substantially increased.

While in accordance with the provisions of the statutes I have illustrated and described the best forms of my invention now known to me, it will be apparent to those 95 skilled in the art that changes may be made in the form of the apparatus disclosed without departing from the spirit of my invention as set forth in the appended claims and that certain features of my invention may 100 sometimes be used to advantage without a corresponding use of other features.

Having now described my invention, what I claim as new and desire to secure by Letters Patent, is:

105

1. A combustion chamber structure for kiln heating provided at one end with air and fuel inlets and an outlet for products of combustion, and formed internally with two passages or chambers extending longitudinally of the structure and communicating, one with said inlets and the other with said outlets at the one end of the structure, and in communication with one another at the opposite end of the structure.

115

2. A combustion chamber structure for kiln heating provided at one end with air and fuel inlets and an outlet for products of combustion, and formed internally with two passages or chambers extending longitudinally of the structure and communicating one with said inlets and the other with said outlets at the one end of the structure and in communication with one another at the opposite end of the structure, and formed with transversely extending open ended channels in its walls.

120

3. A combustion chamber structure for kiln heating provided at one end with air and fuel inlets and an outlet for products 125

130

of combustion and having its body portion formed of tile sections provided with open ended channels extending transversely to the length of the structure and a partition 5 separating the interior of the structure into two chambers or passages communicating at the one end of the structure, one with said inlets, and the other with said outlets, and communicating with one another at the opposite end of the structure.

4. A combustion chamber structure for kiln heating provided at one end with air and fuel inlets and an outlet for products of combustion and having its body portion 15 formed of tile sections provided with open ended channels extending transversely to the length of the structure and a partition separating the interior of the structure into two chambers or passages, communicating at 20 the one end of the structure, one with said inlets, and the other with said outlet, and communicating with one another at the opposite end of the structure, said partition being formed of tile, having open ended 25 passages therein extending transversely to the length of the structure communicating at their ends with the corresponding passages in the side walls of the structure.

5. In a kiln comprising a kiln chamber 30 proper and a combustion chamber structure located in the kiln chamber at the side of a goods receiving space therein and formed with circulating passages for setting up a gravity circulation of the kiln atmosphere upward past the combustion chamber and downward through the goods receiving 35 space, the improvements which consist in a

partition dividing the interior of the combustion chamber into two chambers or passages each extending from one end of the combustion chamber structure to the other and communicating with one another at one end of the structure and provisions at the opposite end of the structure for supplying air and fuel to one of said passages and for withdrawing products of combustion from the other of said passages.

6. In a kiln comprising a kiln chamber proper and two combustion chamber structures in the kiln chamber, one at one side 50 and the other at the opposite side of a goods receiving space therein and formed with circulating passages for setting up a gravity circulation of the kiln atmosphere upward past the combustion chambers and downward through the goods receiving space, the improvements which consist in a partition dividing the interior of each combustion chamber into two chambers or passages each 55 extending from one end of the combustion chamber structure to the other and communicating with one another at one end of the structure and provisions at the opposite end of the structure for supplying air and fuel to one of said passages and for withdrawing products of combustion from the other of said passages, each of said structures having its end with the inlet and outlet connections adjacent the end of the other structure not having such connections.

Signed at New Castle in the county of Lawrence and State of Penn., this 3d day of December, A. D. 1919.

PAUL A. MEEHAN.
